UNITED STATES PATENT OFFICE.

RICHARD MARX, OF PHILADELPHIA, PENNSYLVANIA.

FURNACE.

1,399,638.

Specification of Letters Patent.

Patented Dec. 6, 1921.

Application filed May 6, 1920. Serial No. 379,320.

To all whom it may concern:

Be it known that I, RICHARD MARX, a citizen of the United States, residing in Philadelphia, Pennsylvania, have invented 5 Furnaces, of which the following is a specification.

One object of this invention is to provide a furnace of the general type described and claimed in my application for U. S. Patent 10 #328,442, filed October 4, 1919, whose construction shall be such that a part of its floor within its oxygen free heating chamber may be kept relatively cool, in order to permit of the heat treatment of but a portion 15 of an object such as a die cutter or some other tool placed on the furnace.

A further object of the invention is to provide a novel form of heating furnace which shall permit of the use of a bath of some 20 liquid in permanent communication with its oxygen free chamber, either with a view to maintaining the liquid itself in a fused condition without subjecting it to the oxidizing action of the air, or of making possible 25 the transfer of articles from the interior of the furnace to the liquid without subjecting them to material cooling or oxidation.

These objects and other advantageous 30 ends I attain as hereinafter set forth, reference being had to the accompanying drawings, in which,

Figure 1 is a side elevation of a furnace embodying my invention;

Fig. 2 is a transverse section on the line 2—2, Fig. 1;

Fig. 3 is a section on the line 3—3, Fig. 2;

Fig. 4 is a horizontal section on the line 4—4, Fig. 1;

Fig. 5 is a front elevation of a modification of my invention;

Fig. 6 is a vertical section on the line 6—6, Fig. 5;

Fig. 7 is a side elevation of another form 45 of the invention;

Fig. 8 is a vertical section on the line 8—8, Fig. 7; and

Fig. 9 is a fragmentary vertical section on the line 9—9, Fig. 7.

50 In the above drawings 1 represents the metal inclosing casing of a muffle furnace which is usually supported on a set of legs 2 and has a refractory lining 3. In the interior of this structure is mounted a muffle consisting in the present instance of 55 an elongated metal chamber 4 open only at

its front end and supported above the floor of the furnace chamber by a series of refractory blocks 5.

Said muffle is thus spaced away from 60 the floor, sides, top and back of the furnace chamber and is permanently open through the front of the casing 1, although the combustion space 6 surrounding it is cut off from this front opening. Said space how- 65 ever is provided at its top with suitable outlets 7 for the escape of products of combustion and is designed to be heated by some form of gaseous fuel delivered from two sets of burners 8 discharging into its 70 lower portion from opposite sides.

These burners through pipes 9 and 10 are supplied with a mixture of air and gas from mains 11 and 12 and the proportions of these ingredients may be regulated by 75 valves 13 and 14 connected between the mains and the pipe 10. Extending transversely below the level of the floor of the muffle immediately adjacent its open end is a burner in the form of a pipe 15 having 80 a series of closely spaced relatively small openings formed along its topmost portion designed to supply a series of jets of fuel all in the same substantially vertical plane at or immediately adjacent the entrance to 85 the muffle 4. The fuel for these jets is delivered through a pipe 16 supplied from the mains 11 and 12 and regulated as to its composition by a pair of valves 17 and 18. Upon being ignited the fuel escaping from 90 this burner forms a continuous sheet or curtain of burning fuel which completely closes the opening to the muffle and prevents entrance of air thereto as well as extracts oxygen from its interior.

95 The bottom of the muffle 4, in the present instance immediately adjacent the front thereof, has an outlet opening 19 to which is connected a vertical conduit 20 whose lower end opens below the surface of a 100 liquid such as oil within a container 21 placed under the furnace. A shelf 22 is fixed to the front of the furnace casing so that its top surface is continuous with said muffle floor and serves to support articles 105 removed from or to be introduced to said furnace.

Under conditions of operation the muffle is externally heated to any desired or suitable temperature by fuel delivered from the 110 burners 8 into the space 6, and oxygen is not only excluded but is removed from the

interior of said muffle by the curtain of burning fuel indicated at x in Fig. 1, which is delivered across its open end from the burner pipe 15. After said latter burner has been in operation for a relatively short period only inert gases such as nitrogen and carbon dioxide remain within the muffle so that articles to be subjected to a heat treatment may be introduced through said curtain and raised to the desired temperature without being subjected to the objectionable effects of oxidation or sealing or to the alternate heating and cooling incident upon the use of furnaces having doors.

15 When it is desired to quench the articles after they have attained a desired temperature within the muffle they may be caused to fall through the opening 19 and the conduit 20 into the liquid within the container 21 and obviously in being transferred from the muffle to this liquid they are not exposed to the atmosphere.

If it be desired to raise but a portion of any given object such as a die or cutter to a high temperature under the conditions above described, I may construct the furnace as shown in Figs. 7 to 9 inclusive, in which an air flue or passage 25 is provided under the metal floor or bottom of the muffle at some distance to the rear of the burner 15 for forming the oxygen excluding curtain. This conduit has an inlet opening 26 preferably at its middle portion so that a current of cool air may enter at this point and divide so as to flow in opposite directions under the front portion of the bottom of the muffle and be discharged through outlets 27 in the side of the furnace casing. Obviously that portion of the floor of the muffle between the passage or conduit 25 and the burner pipe 15 is maintained by this air flow at a relatively low temperature, while the remainder of the muffle is raised to and kept at a uniform high temperature by the burning fuel delivered from the burners 8;—it being understood that the conduit 25 is preferably formed in refractory material under the floor of the muffle. Obviously a metal structure such as a die or tool resting on the front part of the muffle floor would have that portion to the rear of the conduit 25 highly heated while its portion in front of said conduit would be kept relatively cool by conduction of its heat to the cool part of the muffle floor.

50 If desired, as illustrated in Fig. 7, I may form the muffle with both ends open to the atmosphere and provide a second burner pipe 15^a extending across the floor of the muffle so as to discharge a curtain of burning fuel across its second open end as indicated at x^1 . With this construction material may be introduced to and removed from the muffle through either end thereof.

55 When a molten metal such as lead is to

be used as a quenching material rather than oil, I may construct the furnace as shown in Figs. 5 and 6 in which form of my invention I provide a hollow metal casing 30 in the form of a box having an inwardly extending flange 31 around its open upper edges. This flange is designed to receive a casing in the form of a metal pot 32 suspended within the body of the box-like casing 30 and extended upwardly in the form of a cover or hood 33 having an opening in its forward side. As illustrated the structure 32—33 is a casting having a perforated conduit 34 extending through it in position to discharge gaseous fuel in the form of a sheet upwardly across the opening into its top 33. This passage or channel is connected to a source of fuel through a pipe 35 and a burner 36 is provided under the pot 32 within the casing 30 so that a body of lead 37 for example may be fused and maintained in a molten condition. Oxidation of this lead is prevented by the curtain x^2 of burning fuel supplied from the conduit 34 across the opening into the top 33 so that articles to be quenched may be introduced through said curtain and plunged into or maintained in the lead in the pot 32 without being exposed to the oxygen in the atmosphere after having passed through said curtain. Obviously the lead may be maintained indefinitely in a melted condition without oxidation as long as the curtain x^2 is provided, it being understood that in this as well as in the other forms of my invention the air and gas supplying said curtain are so proportioned that as the fuel is burned the oxygen is removed from the interior of the muffle or other heating chamber.

105 I claim:—

1. The combination in a furnace of a muffle having an opening; means for heating said muffle; means for maintaining a curtain of burning gaseous material across said opening; and means for causing a portion of the bottom of the muffle to be cooler than the remainder.

2. The combination in a furnace of a muffle having an air passage connected to the atmosphere and extending under a portion of its floor; means for heating said muffle; and means for preventing access of oxygen to the muffle consisting of a device for delivering a burning gaseous curtain across the opening of the muffle.

3. The combination in a furnace of a casting having a heating chamber; means for supplying fuel to said chamber; a muffle mounted in said chamber; means for permitting circulation of air under a portion of the floor of said muffle to maintain the same at a relatively low temperature; and means for excluding oxygen from the muffle consisting of a burner tube positioned to supply a

curtain of burning fuel across the opening of said muffle adjacent that portion of the floor thereof which is maintained at a low temperature.

5. 4. The combination in a furnace of a muffle having an opening; means for maintaining a curtain of burning fuel across said opening to exclude oxygen from the muffle; and a liquid container communicating with 10 the muffle.

5. The combination of a furnace having a muffle provided with an inlet opening and having an opening in its floor; means for supplying a curtain of burning fuel across 15 said inlet opening; and a container cut off from the atmosphere and communicating with said muffle through the opening in its floor.

6. The combination of a furnace having a 20 muffle provided with a delivery opening and an inlet opening; a container having a body of liquid therein; a conduit leading from the

delivery opening of the muffle to a point below the surface of the liquid in the container; and means for forming an air excluding curtain across the inlet opening of the muffle.

7. The combination of a casing having an opening; a container for liquid communicating with said casing; and a burner for supplying a curtain of gaseous fuel across the 30 opening.

8. The combination in a furnace of an inclosing casing; a refractory lining forming a heating chamber; a muffle mounted in 35 said chamber and having an opening to the atmosphere; means for providing a curtain of gaseous fuel across said opening consisting of a burner tube extending adjacent the opening; and means for forming an air conduit under the floor of the muffle to the rear 40 of said opening.

RICHARD MARX.
